CARRYING CASE FOR RAIN WEAR AND UMBRELLA

Ann Walla, Detroit, Mich.

Application September 30, 1954, Serial No. 32,486

Term of patent 14 years

(Cl. D87—5)

Fig. 1 is a front elevation of a carrying case for rain wear and umbrella showing my new design.

Fig. 2 is a rear elevation thereof;

Fig. 3 is a side view taken from the right of Fig. 1; and
Fig. 4 is a top plan view.

I claim:

The ornamental design for carrying case for rain wear and umbrella, as shown.
